No. 691,231.

Patented Jan. 14, 1902.

A. S. BAILEY.

SHAFT TUG ATTACHMENT.

(Application filed July 14, 1898. Renewed Nov. 27, 1901.)

(No Model.)

UNITED STATES PATENT OFFICE.

ALEXANDER STEPHEN BAILEY, OF CRAWFORD, GEORGIA.

SHAFT-TUG ATTACHMENT.

SPECIFICATION forming part of Letters Patent No. 691,231, dated January 14, 1902.

Application filed July 14, 1898. Renewed November 27, 1901. Serial No. 83,941. (No model.)

To all whom it may concern.

Be it known that I, ALEXANDER STEPHEN BAILEY, a citizen of the United States, residing at Crawford, in the county of Oglethorpe 5 and State of Georgia, have invented a new and useful Harness Attachment, of which the following is a specification.

The invention relates to improvements in harness attachments.

10 The object of the present invention is to provide a simple, inexpensive, and efficient device adapted to be readily applied to an ordinary thill-tug and to be connected with a hold-back-strap and arranged on a thill, whereby 15 a horse may be hitched and unhitched without fastening or unfastening the holdback-strap.

10 The invention consists in the construction and novel combination and arrangement of 20 parts hereinafter fully described, illustrated in the accompanying drawings, and pointed out in the claim hereto appended.

25 In the drawings, Figure 1 is a perspective view of an attachment constructed in accordance with this invention and shown applied to a shaft and a thill-tug. Fig. 2 is a sectional view taken longitudinally of the shaft. Fig. 3 is a vertical sectional view. Fig. 4 is a detail perspective view of the device detached.

30 Fig. 5 is a detail sectional view of the shaft, illustrating the manner of mounting the stop thereon.

35 Like numerals of reference designate corresponding parts in all the figures of the drawings.

1 designates a cuff or sleeve adapted to receive a shaft 2 and arranged within an ordinary thill-tug 3, being secured to the same by a strap 4, which passes through the sleeve or 40 cuff and is buckled around the outer face of the thill-tug at the inner side of the shaft, as clearly shown in Fig. 2 of the accompanying drawings; but the strap 4 may be arranged at the outer side of the thill, if desired. In 45 stead, however, of employing a thill-tug the sleeve or cuff may be applied to the harness to take the place of the thill-tug; but in the accompanying drawings the invention is illustrated as applied to the ordinary harness without altering the construction thereof.

50 The cuff, which is arranged in advance of

an annular stop 5, is composed of two split sections 6 and 7 of cylindrical shape, having their split portions located at diametrically opposite points. The inner and outer sections 55 are riveted or otherwise secured together, and by constructing the sleeve or cuff in this manner a clumsy overlapping joint of the leather or other material of which the device is constructed is avoided. 60

The annular stop 5 of the shaft is composed of inner and outer sections 8 and 9, constructed of leather or other suitable material and split at diametrically opposite points to avoid overlapping the material. The stop is tacked 65 or otherwise secured to the shaft to mount it permanently thereon.

The strap 4 receives a ring 10, to which the holdback-strap 11 is connected, and after the holdback-strap is once attached to the ring it is 70 unnecessary to fasten or unfasten it in hitching and unhitching a horse to a vehicle. In hitching an animal to a vehicle the cuffs or sleeves are placed on the shafts and arranged against the stops and the traces are attached 75 to the whiffletree, thereby completing the operation. In unhitching the traces are unfastened, and the horse may then be driven from between the shafts, the sleeves or cuffs sliding outward on the same. 80

The invention has the following advantages: The device, which is simple and comparatively inexpensive in construction, is easily operated and may be readily applied to the ordinary harness without necessitating any 85 alteration in the construction thereof. It possesses great strength and durability and greatly facilitates hitching and unhitching.

Changes in the form, proportion, and minor details of construction may be resorted 90 to without departing from the spirit or sacrificing any of the advantages of this invention.

What I claim is—

A device of the class described comprising 95 a thill-tug designed to be arranged on the thill in the usual manner, a sleeve arranged within the thill-tug and composed of two split sections having their split portions located at different points, said sleeve being detachable, a short strap 4 extending through the sleeve and passing around the thill-tug at one 100

side thereof, and a holdback-strap having a ring linked into the loop formed by the strap 4, whereby the latter is adapted to detachably connect the holdback-strap, the tug and 5 the sleeve, substantially as and for the purpose described.

In testimony that I claim the foregoing as

my own I have hereto affixed my signature in the presence of two witnesses.

ALEXANDER STEPHEN BAILEY.

Witnesses:

WALTER MAXWELL,
J. N. STOKELY.
